UNITED STATES PATENT OFFICE.

FRANCIS E. J. WILDE, OF MEADOWMERE PARK, NEW YORK, ASSIGNOR TO MOTOGRAM CORPORATION, OF NEW YORK, N. Y., A CORPORATION OF NEW YORK.

ELECTRIC SIGN.

Application filed September 23, 1925. Serial No. 57,984.

This invention relates particularly to the control mechanism by which the letters or other characters are caused to traverse the field of a so-called "talking" sign.

5 Special objects of the invention are to simplify and improve the control mechanism, to enable the quick changing of the sign characters and to provide for the operation of a large number of sign characters 10 in a comparatively small and compactly built machine.

Special novel features enabling the attainment of the foregoing and other desirable objects include the handling of the sign 15 characters or patterns in the form of a stack conveniently supported in a magazine and the traversing of such characters through the machine by taking them off one end of such stack and then after running 20 them through the control mechanism, returning them to the opposite end of the same stack.

The details of such construction and various other novel features of the invention are 25 set forth in the following specification.

The drawing accompanying and forming part of this specification illustrates practical embodiments of the invention, but as such illustration is primarily for purposes 30 of disclosure, it is to be understood that structural features may be modified without departure from the spirit and scope of the invention as hereinafter defined and broadly claimed.

35 Figure 1 is a side elevation of the machine with only part of the control board illustrated and indicating some of the patterns in various stages of their travel.

Figure 2 is an enlarged broken vertical 40 section illustrating the operation of the switch controls by the traveling sign characters.

Figure 3 is an enlarged broken sectional view taken as on the plane of line 3-3 of 45 Figure 1, showing the lower portion of the magazine.

Figures 4 and 5 are broken sectional views illustrating the operation of the feed chains in withdrawing the characters from the 50 foot of the magazine.

Figure 6 is a broken detail of a modified form of chain drive.

Figure 7 is a plan of one of the individual character plates.

55 Figure 8 is a cross sectional detail show-

ing the method of holding the contact combs in place.

The body of the sign is not shown in the present illustration and it will be understood that the same may consist of the usual 60 bank of lamps supported in display position and individually governed by suitable switch controls. The switch controls consist in the present disclosure of a series of insulated terminal posts 10, Figure 2, connected with individual lamps or groups of lamps and adapted to be engaged by spring contact fingers 11 positioned alongside and bendable longitudinally into contact with such posts. 70

The posts are shown spaced in rows in a supporting base 12 of insulating material and the spring fingers are shown constructed in the form of "combs" cut from sheet metal to provide in each a row of spring 75 fingers spaced to cooperate with a row of the terminals and all connected together by a back piece 13. These contact combs are indicated as removably supported in between the rows of terminals by sheets of 80 insulating material folded about the backs of the same and providing each an insulating layer 14 at the front of the comb and an insulating layer 15 at the back of the same. This back portion is shown extended 85 substantially to the top of the terminal posts at the rear so as to prevent the spring fingers from snapping backward into contact therewith and the front strip 14 is of less width so as to permit the fingers to readily 90 bend upwardly into contact with the terminal posts in front of the same.

The folded strips of insulation form a partial envelope about the spring combs and by their own resiliency, aid in removably securing the combs in position. To prevent any accidental displacement of the combs they are shown formed at their ends with angularly turned extensions 16, Figure 8, having lugs 17 bent over the rails 18 forming the sides of the frame and caught beneath the cleats 19 secured by the screws 20 over the tops of such rails. With this construction it will be seen that all the combs are held in place by the cleats engaged over the end lugs of the combs and that one or any number of the combs may be pulled out and new ones substituted, after removal of these holding cleats. 100 105

The terminal posts may consist simply of 110

- round rods driven through the insulating base plate 12 and provided with suitable terminal screws 21 at their outer ends. These posts may be equipped at their contact ends with detachable caps 22 frictionally engaged thereover. These contact caps as they wear, may be turned to present new current carrying surfaces and may be readily replaced when necessary.
- 10 The patterns for actuating the switch controls are illustrated as in the form of raised characters 23 of insulating material mounted upon backing plates 24 of generally rectangular outline, also of insulating material.
- 15 These plates travel up through a vertical guideway 25 in position to cause the raised characters thereon to bend the free ends of correspondingly placed spring fingers into contact with their cooperating terminal posts and thus energize the lamps of the sign in a manner to reproduce the outlines of such characters.
- 20 The travel of the patterns is effected by interengagement between such plates and a pair of continuously traveling chains 26 spaced as shown in Figure 3 substantially the width of the plates at a distance greater than the characters on the intermediate portions of the plates.
- 25 The engagement between the plates and chains may be effected in various ways. Thus in Figures 1 to 5 the plates may be provided with projecting pins 27 in their forward corners adapted to enter the open links of the sprocket chains. On the other hand, the chains may carry projecting lugs as shown at 28 in Figure 6 to engage behind the rearward edges of the character plates.
- 30 To provide for the handling of a maximum number of the plates in the machine, said plates are shown as stacked in superposed relation in a vertical magazine 29 mounted at the back of the vertical guideway 25 and in position over the lower horizontal ridges of the chains so that said chains will automatically strip the plates off the bottom of the stack and carry them up through the vertical guideway. To provide for this action the chains are shown as extending over guide rollers 30 at the rear of the machine and through horizontal guide channels 31 beneath the foot of the magazine and from such magazine upwardly through the curved guide channels 32 to the foot of the vertical guideway. The edges of the horizontal guide channels 31 form supports carrying the weight of the stack, as shown in Figures 3 and 5, so that the chains do not carry this weight and are only required to strip the lower plate from the bottom of the stack. The foot of the magazine has a passageway 33 at the front of the same, high enough for a single outgoing plate, as indicated in Figures 4 and 5, and the curved guides extend from this passage so as to

direct the plates and hold them meshed with the chains.

To permit quick loading the magazine may be removable and replaceable as a unit or may be made with one side opening to permit the insertion or removal of a complete stack of the plates. In the illustration the magazine is opened at the rear by having rearward corner strips 34 mounted on spring hinges 35 so that they can be swung back to open the magazine and permit removal and replacement of the plates in stack formation.

The plates taken from the bottom of the stack and carried past the switch controls are automatically returned to the head of the stack in position for passage through the machine again by means consisting in the illustration of a downwardly inclined guide made up of a plurality of free turning rollers 36 extending from the top of the vertical guide rearwardly over the top of the magazine and terminating in a closed guide 37 extending downwardly and doubling forwardly back to the magazine. A guide and stripper 38 at the upper end of the inclined guideway 36 causes the plates as they leave the chains to drop face upwardly on such inclined guide and the plates as they ride down this inclined guide, pass through the reversing channel 37 and drop face downwardly on top of the stack in position to be taken by the chains in their order and be again passed through the machine.

The operation is thus continuous and uninterrupted, the plates being taken by the chains one by one from the bottom of the stack, passed upwardly through the control mechanism and then returned onto the top of the stack in position to pass through the machine again in the same order. If desired, the returning plates may be deflected from the top of the stack and carried away out of the machine. And while the machine is running new plates may be placed in the magazine, for instance, on the return incline 36 and the action of the sign be thus altered while it is in actual operation. To assist in this substitution or changing of the sign characters, the character plates or the characters themselves may have markings on their rearward edges, as shown at 38' in Figure 3 which will be exposed when the plates are in the magazine and thus enable the operator to make any desired changes or substitutions and to accomplish the same without disturbing the proper sequence.

The chains may be of the usual sprocket type and may be driven, for instance, by an electric motor 39 connected by reduction gearing 40 with the lower set of sprockets 41. From these lower sprockets the chains are shown as passing vertically to the upper sprockets 42. The rolls or sprockets 30 guide the horizontal stretches of the chain

at the rear and suitable idlers such as indicated at 43 may be provided to maintain the chains in proper taut condition.

What is claimed is:

1. Apparatus of the character disclosed comprising a stack of disconnected sign patterns, a bank of switch devices having individualized contact elements operable on engagement by said sign patterns to control an electric sign in accordance with the outlines of said sign characters, a guideway for directing said sign patterns past the bank of switch devices in position to engage the contact elements of the switch devices which are positioned in the path of travel of such patterns, means for confining a group of the sign patterns stacked vertically in flat relation one on top of the other and means for automatically abstracting the sign patterns from one end of said stack and traversing them through the guideway to selectively operate the switch devices and for then returning said sign patterns to the opposite end of the stack faced in the same direction in which they were removed from the stack.
2. Apparatus of the character disclosed comprising variously positioned switch devices having individualized contact elements operable on engagement by traveling sign patterns to control an electric sign in accordance with the outlines of said patterns, sign patterns for actuating said switch devices, said sign patterns being disconnected and free for handling independently of each other, means for confining a group of said sign patterns stacked in orderly superposed flat relation one on top of the other and means for automatically abstracting said sign patterns from the bottom of said stack and for traversing the same past the switch devices in position to engage the contact elements of the switch devices which are positioned in the path of travel of the variously outlined sign patterns, said automatic means including guide mechanism for returning the abstracted patterns to the top of the stack and for reversing the returned patterns so that all patterns are arranged in the same order in the stack.
3. Apparatus of the character disclosed comprising pattern plates, raised sign characters carried by and projecting from the faces of said plates, switch devices having individualized contact elements engageable in accordance with their position by the sign patterns of different outlines and operable to control an electric sign accordingly, means for confining a group of the pattern plates stacked in superposed relation and automatic means for withdrawing said plates from the bottom of the stack and for traversing the same past the switch devices and then returning the plates to the top of the stack with the raised characters thereon all faced in the same direction.
4. In apparatus of the character disclosed, loose pattern plates, raised sign characters on said plates, a hopper for supporting said plates in stacked relation one on top of the other, automatic means for withdrawing the pattern plates from one end of the stack and for returning the withdrawn plates to the opposite end of the stack with the raised patterns all faced in the same direction and a bank of variously positioned switch devices located in the path of travel of the pattern plates and adapted to be selectively operated by the sign characters of different outlines.
5. In apparatus of the character disclosed, the combination of loose pattern plates, raised sign characters carried by and projecting from the faces of said plates, a hopper for holding a stack of said plates with the raised characters faced downwardly, switch devices adapted for actuation by said raised characters and automatic means for withdrawing the pattern plates from one end of the stack and for traversing the same past the switch devices and then returning the pattern plates face down to the opposite end of the stack.
6. In apparatus of the character disclosed, switch devices for variously controlling an electric sign, sign patterns, means for holding said patterns stacked in orderly relation and means for traversing said sign characters individually from their stacked position past the switch devices and back to stacked position, including mechanism for turning over the sign patterns to completely reverse the same at one point in their cycle of travel.
7. In apparatus of the character disclosed, switch devices for variously controlling an electric sign, sign patterns, means for holding said patterns stacked in orderly relation and means for traversing said sign characters individually from their stacked position past the switch devices and back to stacked position, including mechanism for turning over the sign patterns before their return to the stacked position.
8. In apparatus of the character disclosed, sign patterns, a hopper for loosely confining the same in stacked relation, switch devices for variously controlling an electric sign, automatic propelling and guiding means for traversing the patterns from the bottom of the stack past the switch devices and back to the top of the stack, said means including a reversing guide at the top of the stack for turning over the sign characters as they are returned to stacked relation.
9. In apparatus of the character disclosed, sign patterns, a hopper for confining a group of said patterns, channel guides at the foot of said hopper, chains running in said guides across the bottom of said hopper and having disengageable connection with the patterns for withdrawing the same individ-

- ually from the bottom of the hopper, switch devices for variously controlling an electric sign, guide means for directing the patterns past said switch devices, said chains 5 operating in conjunction with said guides to traverse the patterns in operative relation past the switch devices.
10. In apparatus of the character disclosed, loose sign patterns having distinguishing indicia on the edges thereof, a hopper for confining said patterns with the identifying indicia exposed, switch devices for variously controlling an electric sign and automatic means for traversing the identified patterns from the hopper past the switch devices.
11. In apparatus of the character disclosed, the combination of terminal posts arranged in spaced relation, contact caps 20 movably engaged over the same, movable contacts for engagement with said caps and sign mechanism for automatically actuating said movable contacts.
12. In apparatus of the character disclosed, an upright magazine, sign characters loosely stacked in superposed relation in said magazine, sprocket chains traversing the bottom of the magazine, said chains and characters having interengaging portions whereby 25 by said characters will be abstracted by said chains one by one from the bottom of the magazine, an upright guide for the characters engaged with the chains and sign control switch devices positioned opposite said 30 guide for actuation by the sign characters in their travel in said guide.
13. In apparatus of the character disclosed, sign characters, a vertical magazine for supporting a stack of the same, a guide 40 for said characters, a chain traversing said guide and extending from one side to the other past one end of the magazine, said chain and characters having interengaging parts whereby in the travel of the chain 45 across the end of the magazine said characters will be withdrawn from the magazine and passed through the guide by said chain, sign control switch devices positioned adjacent the guide to be actuated by said characters and means for automatically returning 50 the characters from said guide to the opposite end of the magazine.
14. In apparatus of the character disclosed, sign characters, a magazine for supporting a stack of the same, a guide for said characters, a chain traversing said guide and one end of the magazine, said chain and characters having interengaging parts whereby 55 said characters will be withdrawn from the magazine and passed through the guide by said chain, sign control switch devices positioned adjacent the guide to be actuated by said characters and means for automatically returning 60 the characters from said guide to the opposite end of the magazine, including
- a guideway for receiving the characters from the guide and a reversing chute for turning the characters over as they enter the magazine.
15. In apparatus of one character disclosed, sign characters, a magazine for a vertical stack of said characters, channels at the foot of said magazine, chains traveling in said channels, said chains and characters having interengaging means enabling the 70 chains to withdraw the lowermost characters from the magazine and sign control switch devices actuated by the characters propelled by said chains.
16. In apparatus of the character disclosed, sign characters having indications on the edges of the same, a magazine for supporting said characters with the edges exposed to show said indications, means for automatically withdrawing said characters 75 from said magazine and sign control switch devices actuated by said characters in the automatic travel of the same.
17. In apparatus of the character disclosed, sign characters, a magazine for a 80 vertical stack of said characters, open channels extending beneath the foot of said magazine for supporting the stack of characters, chains traveling in said channels, said chains and characters having interengaging means 85 for effecting the automatic withdrawl of the bottom characters in the stack and signal control switch devices disposed in the path of travel of the characters propelled by the the chains.
18. In apparatus of the character disclosed, spaced chains, supporting plates, said plates and chains having cooperating parts whereby the plates will be propelled by said chains, raised sign characters mounted on 90 the plates and adapted to travel in the space between the chains, sign control switch devices disposed in the space between the chains for actuation by said characters and means for automatically effecting disengagement of the character plates from the chains.
19. In apparatus of the character disclosed, an upright guideway, chains having upright stretches traversing said guideway and horizontal stretches extending rearwardly from the foot of the same, a magazine over the horizontal stretches of said chains, sign characters supported in said magazine in position to be engaged by 100 said horizontal stretches of the chains, a guideway inclined downwardly from the upper portion of the first guideway to the upper end of the magazine and sign control switch devices positioned in front of the first guideway for actuation by the sign 105 characters.
20. In combination, sign controls comprising terminals and spring contacts bendable into engagement therewith, raised sign characters for bending selected ones of said bend- 110

- able contacts, said sign characters being disconnected from each other, a magazine for said loose sign characters and means for automatically circulating said characters from said magazine past the bendable contacts and back into said magazine.
21. In apparatus of the character disclosed, insulated terminal posts, contact caps removably engaged over the same, movable contacts for engagement with said caps and sign mechanism for automatically actuating said movable contacts.
22. Sign control mechanism comprising an insulating base, rows of terminal posts carried by said base, contact combs having spring fingers for engagement with the posts and folded strips of insulation engaged over the back portions of said combs and held between the rows of terminal posts.
23. Sign control mechanism comprising an insulating base, rows of terminal posts carried by said base, contact combs having spring fingers for engagement with the posts and folded strips of insulation engaged over the back portions of said combs and held between the rows of terminal posts, said combs having end lugs, supporting rails over which said end lugs are turned and cleats detachably engaged over said end lugs for releasably holding all the combs in position.
24. In combination, an insulating base, terminal posts mounted on said base, spring contacts for engagement with said posts having angularly turned end lugs and fastening cleats removably engaged with said end lugs for simultaneously releasably securing all of said contacts in position.
25. In apparatus of the character disclosed, sign control switch devices, loose sign patterns for variably actuating the same, a vertical magazine positioned to the rear of said sign controls for confining a group of the sign patterns stacked in vertical relation, a propelling chain extending from the magazine forwardly past the sign controls, said chain having a substantially horizontal reach extending across the foot of the magazine and interlocking portions on said chain and sign patterns engageable in the horizontal travel of the chain past the foot of the magazine, whereby said patterns will be extracted one by one from the bottom of the magazine and be carried into actuating engagement with the sign controls.

In witness whereof, I have hereunto set my hand this 9th day of September, 1925.

FRANCIS E. J. WILDE.
